UNITED STATES PATENT OFFICE.

WILLIAM N. WHITELEY AND WILLIAM BAYLEY, OF SPRINGFIELD, OHIO.

HARVESTER.

SPECIFICATION forming part of Letters Patent No. 330,654, dated November 17, 1885.

Application filed July 25, 1884. Serial No. 138,739. (No model.)

To all whom it may concern:

Be it known that we, WILLIAM N. WHITELEY and WILLIAM BAYLEY, both of Springfield, in Clark county, in the State of Ohio, have invented new and useful Improvements in Harvesters; and we do hereby declare that the following is an accurate description of the same, reference being had to the accompanying drawings, wherein—

10 Figure 1 is a perspective view of our improvement, and Fig. 2 is a plan of the machine.

This invention relates to the means for controlling the flexible tongue of a harvesting-machine; and it consists, first, in extending 15 one side bar of the main frame forward of the front end of said frame to provide a seat for the controlling - lever in advance of the joint of the tongue; second, in the driver's seat mounted upon the lateral brace of the tongue 20 in advance of the tongue-joint, &c.

The main frame is rectangular, and is composed of the bars t t^2 , properly framed together at their intersections. They inclose the main wheel, and support the axle-bearings for the 25 same, as well as the bearings for the pinion-shafting and other attachments and operative parts of the harvester. The inner side bar, t^2 , of the frame projects forward of the front cross-bar, t , and at its forward end supports 30 the joint-plate j for the lever a^3 , whereby the driver controls the tongue s^2 . The joint-plate j is also provided with a notched segment, k , and said lever is provided with a locking-bolt, l , to engage therewith and retain the tongue 35 in any desired position with reference to the plane of the frame. The tongue is jointed to the frame by a joint - bolt, u^2 , which passes through both tongue and inner bar, t^2 , near to the front cross-bar, t , and the lever a^3 is connected to the tongue in advance of the forward end of the inner bar, t^2 , by means of a link, b^3 .

The tongue s^2 is supported against lateral strains by means of a diagonal brace, b , which is rigidly secured to the side of the 40 tongue at or near the joint whereby the link b^3 is united to it, and it extends diagonally therefrom to the outer front corner of the frame at d , to which it is jointed in line with the axis of the bolt u^2 . There is also from the 45 inner front corner of the main frame to the inner shoe a brace, y^2 , and from this brace, near its forward end, a strap, z^2 , is extended to

the end of the tongue joint-bolt u^2 outside of the tongue to support said bolt outside the tongue. The lateral brace b supports the 55 driver's seat w^2 and foot-board v^2 , and the tool-box x^2 we also attach to the same brace, whereby the weight of the driver and the contents of the tool-box are supported upon the tongue in advance of its joint-connection with the frame, and it is thereby rendered more efficacious in counterbalancing the weight of the platform and binding mechanism, which are in rear of the main-wheel axle.

Having described our invention, what we 65 claim as new is—

1. A main frame surrounding and supported by a main wheel, a platform, cutting and binding apparatus attached to and supported by said frame in rear of the main wheel, and a 70 forward extension of the inner side bar, t^2 , substantially as described, combined with a tongue, s^2 , pivoted to said forwardly-extended side bar, a diagonal brace, b , and a driver's seat and foot-board mounted on said diagonal 75 brace, whereby the weight of the driver is supported by the tongue in advance of its joint-connection to the main frame, substantially as set forth.

2. The main frame t t^2 , surrounding and supported by the master-wheel a^2 , a cutting apparatus, platform, and binding apparatus attached to and supported by said frame in rear of the main wheel, combined with the tongue s^2 , jointed to a forward extension of the side 85 bar, t^2 , the diagonal brace y^2 , and strap z^2 , whereby the outer end of the bolt u^2 is supported.

3. A main frame surrounding and supported by the main wheel a^2 , and the forward extension of the inner side bar, t^2 , and the tongue s^2 , jointed to the main frame, the diagonal brace b , rigidly secured to the tongue just in advance of the end of the extended side bar, t^2 , and the lever a^3 , mounted upon the extended 95 side bar, t^2 , at its extremity, and the link b^3 , whereby said lever is jointed to said tongue, substantially as set forth.

WILLIAM N. WHITELEY.
WILLIAM BAYLEY.

In presence of—

F. B. FURNISS,
SOL. J. HOUCK.
